UNITED STATES PATENT OFFICE.

THEODORE H. KRUSE, OF ARVADA, COLORADO.

RAILROAD-TIE.

1,370,025.

Specification of Letters Patent. Patented Mar. 1, 1921.

Application filed June 4, 1920. Serial No. 386,455.

To all whom it may concern:

Be it known that I, THEODORE H. KRUSE, a citizen of the United States, residing at Arvada, in the county of Jefferson and State 5 of Colorado, have invented a new and useful Railroad-Tie, of which the following is a specification.

One object of this invention is to provide a metallic tie of novel form, and another object of the invention is to provide a novel 10 and efficient rail holding means.

It is within the province of the disclosure to improve generally and to enhance the utility of devices of that type to which the 15 invention appertains.

With the above and other objects in view, which will appear as the description proceeds, the invention resides in the combination and arrangement of parts and in the 20 details of construction hereinafter described and claimed, it being understood that, within the scope of what is claimed, changes in the precise embodiment of the invention shown can be made without departing from 25 the spirit of the invention.

In the drawings:—

Figure 1 shows in side elevation, a tie and rail fastening means constructed in accordance with the invention; Fig. 2 is a top 30 plan; Fig. 3 is a section on the line 3—3 of Fig. 1; and Fig. 4 is a section on the line 4—4 of Fig. 2.

The tie forming the subject matter of this application preferably is made of a single 35 sheet of metal disposed in tubular form to fashion oppositely convexed side portions 2. The bottom of the tie 1 is inwardly bulged as shown at 3 to define a longitudinal recess 4. Reinforcements 5 extend across the 40 recess 4, the ends of the reinforcements being connected with the bottom portion of the tie in any suitable way. If desired, the ends of the reinforcements may be extended through the bottom portion of the tie and be clenched 45 thereon as shown at 6. The edges of the strip or plate out of which the tie is made are overlapped at the top of the tie as shown at 7, and are provided with transversely elongated slots 24.

Owing to the fact that the tie 1 is inwardly bulged on its bottom as shown at 3, to define the longitudinal recess 4, the tie 50 will hold well on the ballast. The reinforcements 5 not only prevent the tie from flattening out on the bottom, but, at the same

time, they coöperate with the ballast, to prevent the tie from moving endwise.

The overlapped parts 7 of the tie 1 support a rail 8. On opposite sides of the rail 8 are located braces 9, each brace 9 including 60 a base 10 shaped as indicated at 11 to coöperate with the base flange of the rail 8. each brace including an upstanding wing 12, there being a buttress 14 extending between the base and the wing. In the base of the 65 brace 9 there is an opening 22 alined with the slot 24 in the overlapped parts 7 of the tie 1. The base 10 of the brace 9 is supplied with a depending lug 15 extended through the slot 24 and provided with a lateral 70 shoulder 16. Spring arms 17 are secured at one end, as indicated at 18 to the base 10 of the braces 9, each arm being supplied with a tapered finger 20, the finger being secured to the spring arm in any suitable 75 way, as indicated at 21. The arm 17 forms means for holding the finger 20 yieldably in the opening 22 of the brace and in the slot 24 of the tie.

In practical operation, the brace is placed 80 against the rail 8, the lug 15 entering the slot 24 of the tie, the free end of the spring arm 17 being pulled upwardly so that the finger 20 does not project through the opening 22 in the brace and through the slot 24 85 in the tie. The finger 20 then may be driven downwardly by a hammer blow and, since the finger is tapered, the finger, coöperating with the overlapped portions 7 of the tie, at one end of the slot 24, and with the lug 90 15, will force the lug to the right (Fig. 3) until the shoulder 16 is engaged beneath the top portion of the tie, all of which will be obvious when Fig. 3 of the drawings is noted.

It will be obvious that there is disclosed in this invention, a railroad tie of novel and useful form and a rail fastener of peculiar efficiency.

Having thus described the invention, what 100 is claimed is:—

1. A railroad tie fashioned from a single sheet of material disposed in tubular form, the edges of the sheet being overlapped at the top of the tie, the bottom of the tie being 105 inwardly bulged to form a longitudinal recess; and a reinforcement extended across the recess and connected to the bottom of the tie on opposite sides of the recess.

2. A railroad tie of tubular form, pro- 110

vided in its bottom with a longitudinal recess; and reinforcements extended across the recess, the reinforcements being extended through the bottom portion of the tie and being clenched thereon, at opposite sides of the recess.

3. In a device of the class described, a tie having an opening in its top; a brace on the tie and provided with a lug extending into the opening, the lug having a shoulder adapted to engage beneath the top of the tie when the brace is moved laterally of the tie; a spring tongue secured at one end to the brace; and a tapered finger on the tongue,

the finger extending into the opening and co-operating with the tie to move the brace laterally and to cause the shoulder to engage beneath the top of the tie, the tongue constituting means for holding the finger releasably in the opening.

In testimony that I claim the foregoing as my own, I have hereto affixed my signature in the presence of two witnesses.

THEODORE H. KRUSE.
